FEED MECHANISM FOR KNITTING MACHINES.

Application filed August 3, 1921. Serial No. 489,441.

This invention concerns knitting machines and relates more particularly to yarn feeding and changing means for use therewith.

In the manufacture of knit goods such, for example, as sweaters, bathing suits, etc., it is often desirable to change the yarns at intervals whereby to produce ornamental stripes in the fabric. In a machine of the fixed needle type, wherein the yarn is fed by means of a burr-wheel, it is substantially necessary, in order to secure positive feeding of a new yarn, that the end portion of the yarn which extends beyond the guide eye be held taut as it approaches the burr-wheel. It is also necessary, for efficient operation, that such run of yarn be entered radially between two of the needles and at a sufficient distance in advance of the burr-wheel to permit the yarn to reach its low, or feeding position before encountering the burr. While mechanisms of various kinds have been devised from time to time with the object of changing the yarn automatically, they have in most instances failed in one way or another to provide for all of the above-noted and necessary functions. In some of such devices the stiffness of the lightly tensioned yarn is depended upon entirely for causing the yarn end, when entered between two needles, to feed with the needles to the burr-wheel. In other mechanisms the yarn clamp employed for holding the ends of the idle yarns is so close to the sinker burr-wheel that insufficient time is allowed for the entering yarn to reach its feeding point before encountering the burr-wheel, which, in such cases, tends to lift the yarn out of engagement with the needles. In some devices, the movement of the yarn finger to feeding position is such that the run of yarn between the guide eye and clamp becomes slack and, as the sinker burr-notches are necessarily small, the engagement of the yarn therewith is rendered uncertain. Thus when it is attempted to employ such appliances, there is little certainty as to the exact point in the fabric at which the overlap of the yarns will occur, while the formation of ladders and press-offs is of common occurrence.

The difficulties encountered in the attempt to change the yarns by mechanical means, especially when dealing with frictional yarns, that is to say, those having an un-

even or fuzzy surface, have in fact been so great that it is still the common practice to make the desired yarn changes as a manual operation, relying upon the alertness and skill of the workman to make the change at the proper point in the width of the fabric and after the completion of the desired number of courses. Such a mode of changing the yarns not only tends to cut down production but introduces an element of possible error which in many instances results in defective fabric.

The object of the present invention is to overcome the difficulties commonly experienced in the changing of yarns for forming transverse stripes in the knitted fabric as above pointed out. To this end it is proposed to provide simple and reliable mechanism capable of manipulating yarns of any usual character or material and operative automatically to present the new yarn with certainty to the needles while removing the old yarn to provide an overlap of minimum extent consistent with good knitting, the mechanism being so devised that the new yarn shall be entered with accuracy at a predetermined needle wale. It is also proposed to provide yarn changing mechanism of such a character that when employed with a stitch burr, the adjustment of the latter will have no appreciable effect upon the proper introduction and withdrawal of the yarns.

In accordance with one arrangement, such mechanism may comprise yarn guiding fingers having guide openings or eyes movable from the operative or yarn feeding point in front of the needles up and over the needles to a position behind the same and below the plane of the tops thereof at the yarn receiving point. Such yarn fingers when in such inoperative position behind the needles may cooperate with yarn clamping means capable of temporarily retaining the end of the idle yarn at a position very closely adjacent its point of emergence from the guide eye. Such clamping means may be of any desirable type and if the device be employed with a burr-wheel machine having fixed needles, may be mounted upon the cloth hold-down which will be somewhat widened for this purpose. For severing the idle run of yarn subsequent to its clamping, suitable automatically operative means may be employed, such means preferably operating to

sever the yarn by a hammer blow and also being mounted upon the cloth hold-down. For providing certainty in operation in the changing of woolen or like frictional yarns, 5 the yarn guide fingers, when in idle position, may stand between yarn separator devices, such for example as spaced pins or thin upstanding partitions, whereby the idle yarns are kept separate while engaged by 10 the clamping means, and whereby the yarn end, in withdrawing from the clamp is caused to traverse a path in which it contacts with the other idle yarn or yarns to a minimum extent.

15 With this arrangement, the movement of the idle yarn guide from inoperative position within the needle circle will serve to "slice" the ingoing yarn sharply down between adjacent needles, and as the yarn end 20 will still remain in the clamp, the yarn will immediately be drawn under tension from the supply and presented in a positive manner to the stitch burr for reception by the needle hooks, whereupon the end of the 25 yarn will be withdrawn from the clamp by the movement of the needle cylinder relatively to the latter.

For the proper actuation of the various operative instrumentalities above referred 30 to, a pattern drum or drums may be employed having thereon suitably disposed indications for initiating the movements of such instrumentalities in the desired order. Suitable means will also be provided for 35 imparting the necessary movement to such drum or drums at the desired intervals for securing the pattern required. A master pattern may be provided for operatively setting a movable cam or similar device carried by the needle cylinder. Preferably the 40 cam, when set, will operate merely to position certain elements of the drum moving mechanism, the cam immediately returning to inoperative position. The turning of the 45 drum or drums may then be accomplished in an absolutely accurate manner and in perfectly timed relation to the rotation of the needle cylinder by one or more properly configurated cams fixed to the latter and 50 rotating therewith. This arrangement permits the entrance and withdrawal of the yarns with certainty as respects predetermined needle wales and is particularly desirable in machines wherein a plurality of 55 feeds with corresponding yarn changing devices are employed, the actuating cams in such case serving successively to actuate the pattern drums at the several feeds in like manner.

60 A preferred arrangement of parts, well exemplifying means suitable for use in carrying the above objects into effect is illustrated in the accompanying drawings in which,—

65 Fig. 1 is a fragmentary plan view of a

knitting machine of ordinary construction illustrating the yarn changing mechanism of the present invention as applied thereto;

Fig. 15 is a fragmentary side elevation of 110 a part of the needle cylinder showing an adjustable cam thereon, together with the means for controlling the operative position of such cam.

Fig. 16 is a vertical cross section on the line *x*—*y* of Fig. 15 showing certain of the parts therein illustrated;

Fig. 16^a is a horizontal section on a line 115 such as *s*—*t* of Fig. 15;

Fig. 17 is a diagrammatic plan view illustrating certain fixed operating cams carried by the needle cylinder, together with the levers actuated thereby;

Fig. 18 is a diagrammatic side elevation 120 illustrating the vertical relationship of the cams of Fig. 17;

Figs. 19 to 24 inclusive are diagrammatic 125 plan views of the yarn guides and clamping devices showing the relative positions of the parts at various stages of the changing operation; and thereafter.

Fig. 25 is a plan view and Fig. 26 a side elevation of the yarn clamping levers and 130

associated parts to larger scale; Fig. 27 is a fragmentary vertical cross section on the line 27—27 of Fig. 2 and to larger scale; and Fig. 28 is a fragmentary cross section in the 5 plane of Fig. 16 showing the method of co-operation of a movable cam device carried by the needle cylinder with certain actuating arms for the yarn changing mechanism.

Referring particularly to Figs. 1, 15 and 10 16, the bed of the machine is indicated at 1, such bed being provided with a suitable opening within which the depending flange 2 of the needle cylinder 3 has a running fit. The needle cylinder 3 is provided with suitable 15 grooves for the reception of spring beard needles 4, such needles being retained in position in the usual manner by segmental clamps. Mounted upon the bed 1 at the feeding point or points is a fixed frame comprising the base 6, Figs. 2 and 3, from which the flange members 7, 8, extend in opposite directions respectively. These flange members are provided with raised elongated bosses 9, 10, provided with arcuate slots 11, 20 25 30 35 40 45 50 55 60 65 70 75 80 85 90 95 100 105 110 115 120 125 130

12. Mounted for adjustment longitudinally of the slot 11 is a post 13 upon whose upper end is adjustably secured the rod 14 which carries the loop depresser wheel 15, such wheel being indicated in dotted lines in Fig. 1. Adjustably mounted within the slot 12 is a stud 16 which serves to secure the bracket in proper position upon the frame. This bracket carries the post 18 which serves as a support for the stitch burr or loop wheel indicated in dotted lines at 19 in Fig. 1. The post 20 is also mounted for adjustment along the slot 12, such post having the rod 21 adjustably secured at its upper end, this rod serving as the support for the beard presser 22. The supporting frame is provided with a vertically extending portion 23, Fig. 2, from which rise the spaced parallel web members 24, such web members serving to support an element providing a flat supporting surface 25. Secured by means of screws, as 26, to the supporting surface 25, is a bracket 27, such bracket being bifurcated to form the spaced depending arms 28, 29 respectively. These arms, as indicated in Figs. 3 and 7, are united at their lower ends by the bar 30, such bar being continued to one side of the member 27 as indicated at 31, Fig. 1. The bar 30 with its continuation is arranged to lie immediately within the needle circle and performs the function of the usual cloth hold-down, being provided with a suitably formed under surface for this purpose. The portion 30 of this bar is substantially wider in a radial direction than the portion 31 thereof, the portion 30 having an additional function which will be more fully described hereinafter.

Between the web members 24 and beneath the supporting surface 25 are arranged a plurality of yarn guide fingers 32, 33, 34

respectively. These yarn guide fingers are of similar form and one of such levers, for example that denoted 32, is shown in detail in Fig. 13. This finger, as indicated in such figure, is of elongated form and is provided with a substantially vertical yarn guide eye 35 adjacent its free or inner end. From its lower edge depends a lug 36 having an opening 37 to which is secured one end of a spring 38, the opposite end of said spring being connected to a pin 39 fixed in the supporting frame. The yarn finger is also furnished with an elongated cam slot 40, such cam slot serving for the reception of a pair of pins 41, 42 respectively, which extend between the web members 24 and which are fixedly secured therein. The pins 41, 42 are common to the several yarn fingers and serve to guide the latter in their movement toward and from yarn feeding position. The outer ends of the yarn fingers are provided with curved surfaces at 43 for engagement with an actuating lever hereinafter described.

For severing the idle yarn as it is withdrawn from knitting position, a yarn cutter is provided, such cutter being shown in detail in Fig. 14. This yarn cutter comprises a lever 44 having at its inner end the cutting element 45. While under some circumstances this element may be sharpened, it is preferred under most conditions of use to form the cutter as a blunt implement which serves to sever the yarn by impact. At an intermediate point in the cutter lever 44 there is provided an opening 46 for the reception of an end of a coil spring 47, the opposite end of such spring being connected to the frame member 6. At the point 48 the lever 44 is provided with an opening through which passes a pin 49 upon which the lever is pivoted, such pin extending transversely between the webs 24 and being fixed therein. At its outer extremity the lever 44 is also provided with an opening for the reception of a bolt or pin 51 secured in the upper end of a lever 52, the lever 52 being also pivoted upon the pin 49. As thus constructed, the lever 52 essentially forms an arm of the lever 44 and serves to actuate the latter.

For retaining the ends of the idle yarns when the corresponding yarn fingers are in operative position, a suitable clamping mechanism is provided, such clamping mechanism being shown in detail in Figs. 7 to 10 respectively. As indicated in Figs. 8 and 9, the upper surface of the member 30 is provided with a dove-tail slot 53 extending longitudinally thereof. At its central portion this slot is covered by a plate 54 secured to the member 30 by means of screws 55 or in other desired manner, this plate serving as a support for the ends of the idle yarn guide fingers and also providing a sur-

face against which the idle yarns may be clamped. Within the slot 53 and at each side of the plate 54 are the slides 56, 57 respectively, such slides being provided with 5 upstanding ears 58, 59. These ears are vertically slotted, and within such slots are arranged the ends of the clamp levers 60, 61, respectively. These clamp levers are pivoted to the ears 58, 59 by means of pivot 10 pins 62, 63 respectively, such pivot pins extending outwardly from the side walls of the respective ears 58, 59 as indicated in Fig. 8, these extending portions serving for engagement by operating devices hereinafter 15 to be described.

The clamp levers 60, 61 extend in opposite directions from their pivots and have their free extremities in overlapping relationship upon the plate 54 as indicated in Fig. 8. For 20 normally retaining the clamping members 60, 61 in engagement with the upper surface of the plate 54, springs 64, 65 are provided. These springs are of bow form being secured, as by means of screws 66, 67, to the 25 upper surfaces of the slides 56, 57, respectively. These springs extend upwardly and over the ears 58, 59 and are provided at their free extremities with enlarged heads 68, 69, providing spaced, downwardly depending lugs which take over the upper edges of the clamp members 60, 61 respectively. Extending laterally from each of the clamp members 60, 61 is an ear 70, 71 respectively, such ears being arranged to 30 overlie the fixed blocks 72, 73 respectively. These blocks are secured to the member 30 inwardly of the clamping members 60, 61 by means of bolts or screws 74, 75. At their adjacent ends the members 72, 73 are provided with inclined or cam surfaces such as 35 76. Mounted upon the members 72, 73 are the cam carrying blocks 77, 78, such blocks being provided with openings 79, 80 respectively, see Fig. 8, for the reception of spin- 40 dles as 81, upon which are secured the cam members 82, 83 respectively. These cam members, as indicated in Fig. 10, each comprise the inclined surfaces 84, 85, and the horizontal surfaces 86, 87. Each cam device 45 is also provided with a laterally extending lug or ear such as 88, with which engages a coil spring 89 having its other end seated within a socket in a cover plate 90. The members 72, 77 and 90 are all secured together and to the member 30 by means of the aforesaid screws 74, 75. The free ex- 50 tremity of the cover plate 90 overlies the cam surface 76 and the corresponding movable cam member and assists in retaining the cam members in operative position. Bell crank levers 91, 92 are pivoted upon the supporting members 28, 29 respectively, as by means of screws or bolts 93, 94. Such bell crank levers comprise the outwardly 55 directed arms 95, 96 to which are attached

the tension springs 97, 98 respectively. The lower ends of said springs are secured to lugs 99, 100, extending outwardly from the members 28, 29 respectively. The bell crank levers 91, 92 also comprise the downwardly extending arms 101, 102, whose lower ends, as indicated in Fig. 7, lie within the respective slots 53 and bear against the slides 57, 56 respectively. The levers 91, 92 with their actuating springs 97, 98, thus normally urge 70 the slides 57, 56 inwardly toward the plate 54 and into contact with a centrally disposed stop pin 102^b extending transversely across slot 53, whereby the lugs 70, 71 of the respective clamping members are removed 80 from engagement with the actuating cams above described.

The rear edge of the plate 54 is turned up, as indicated in Fig. 9, to form a flange 103, such flange serving in a positive manner to prevent overthrow of the yarn fingers when moving to idle position, the yarn fingers being provided with surfaces such as 104 for engagement with said flange. At its left-hand edge the plate 54 is also provided with an upstanding flange 105, such flange being provided with the vertical slot or opening 106 through which the clamping member 61 with its spring extends. At its forward edge the member 105 is provided with a downwardly extending lug 107 having at its end the foot 108, such foot being spaced slightly above the upper surface of the plate 54, whereby to permit the passage of yarns between such foot and the plate. To the left of the flange 105 the plate 54 is extended, as indicated at 109, Fig. 8, to provide a horizontal surface for engagement by the yarn cutting implement, such surface serving to support the yarns to be severed. 100 105

For actuating the several yarn fingers, levers such as 110, corresponding to the several yarn fingers are provided, one of such levers being shown in detail in Fig. 13. These levers are pivoted to turn upon a rod 111 secured in a pair of spaced and rearwardly extending arms as 112 extending from the supporting frame. Each of the levers 110 is provided near its free extremity with a surface 113 for engagement with 110 the surface 43 of the corresponding yarn finger and at a point adjacent its pivot each lever is also provided with a lug 114 having a cam surface 115 for engagement with suitable pattern indications carried by a pattern 115 drum 116. This pattern drum is fixed to, or integral with, a shaft 117, such shaft being supported by arms 118, 119, extending rearwardly from the supporting frame. The journal openings for the shaft 117 are 120 preferably provided partly in the arms 118, 119 and partly in bracket members 120, 121, respectively, secured to the arms 118, 119 as by means of bolts 122, 123. 125

For moving the clamping members in op- 130

position to the springs 97, 98, the levers 124, 125 are pivoted at the points 126, 127 respectively upon the upper surface of the member 25. While these levers may be integral from end to end if desired, they are herein illustrated as comprising inner and outer members secured together by the pivot pins and by screws or bolts 128, 129 respectively. The inner members of said levers extend downwardly below the supporting bracket arms 28, 29, as indicated in Figs. 2 and 3, and at their free extremities 130, 131 the arms are arranged to engage the opposed faces of the pins or bolts 62, 63 respectively.

The outer members of the levers 124, 125 indicated at 132, 133 respectively, are provided with studs 134, 135 extending downwardly therefrom. The stud 134 is arranged 20 for engagement with the cam teeth 136 of a pattern disk or wheel 137, such disk or wheel being arranged to turn freely upon the shaft 117 and being held in proper position thereon by engagement with the pattern wheel 116 and with a lever 138 also pivoted upon the shaft and hereinafter described more at length. As indicated in Fig. 1, the cam lugs or teeth upon the pattern wheel 137 comprise the inclined faces 139 and the substantially straight faces 140, such teeth being spaced equally about the periphery of the pattern wheel. As shown in Fig. 4, the pattern wheel is preferably of dished formation, and within the hollow outer side 30 thereof is secured a ring 141 having ratchet teeth 142 thereon. This ring may be secured to the wheel 137 by means of screws 143 or in other desired manner.

The lever member 138, hereinbefore described, is arranged between the outer surface of the ring 141 and the adjacent surface of the bearing bracket arm 118. This lever member is provided adjacent its lower extremity with an opening for the reception 40 of a pin 144, upon which is mounted a pawl 145. This pawl is provided at one end with a tooth 146 lying in the plane of the ratchet ring 141 and engageable with the teeth 142 thereof. At its opposite end, the pawl 145 is provided with a pin 147 extending inwardly in the plane of the lever 138 and to which the end of a coil spring 148 is attached. The opposite end of said spring is secured to an ear 149 extending outwardly from the lever 50 138. At a point below the pivot 144 of the pawl 145, the lever 138 is provided with an outstanding pin 150 for a purpose herein-after to be described.

The stud 135 of the lever member 138 is also arranged for engagement with cam teeth 151 of a pattern wheel or disk 152, such disk being arranged upon the opposite side of the pattern drum 116 from the wheel 137 previously described, and also being loose upon 60 the shaft 117. The wheel 152 is provided with a ratchet ring 153 having ratchet teeth 154 engageable with a pawl 155 pivoted at 70 156 upon a lever 157, such lever being interposed between the wheel 152 and the bearing bracket 119. The lever 157 is also free to turn upon the shaft 117 and has a lug 158 to which is connected one end of the coil spring 159, the opposite end of which is secured to the pawl 155 at the point 160. The lever 157 is provided with an outstanding pin 161, the purpose of which will be described hereinafter. The bracket members 120, 121, respectively, are provided with outwardly projecting arms 162, 163 having the bosses 164, 165 at their outer extremities. These bosses 80 are provided with sockets within which are arranged pins 166, 167 respectively, such pins resting at their inner ends against coil springs seated within the sockets and which tend to project the pins from the 85 sockets. Secured to the respective pins are plates 168, 169 respectively, such plates bearing against the adjacent faces of the wheels 137, 152 respectively, and serving as brake members to prevent accidental displacement 90 of such wheels or overthrow thereof when actuated by their driving pawls. Secured upon the inner face of the wheel 152 is a disk 170, which may be connected to the wheel 152 by means of screws 171 or in other 95 desired manner. The disk 170 is provided with peripherally spaced cam teeth 172 as indicated in Figs. 2 and 14 respectively. These cam teeth are provided with inclined surfaces 173 and with substantially radial 100 surfaces 174, and may if desired, have flat peripheral faces interposed between said surfaces, as indicated at 175. The teeth 172 cooperate with a member 176 carried upon the lever 52 hereinbefore referred to, such cam 105 teeth serving to actuate said lever, whereby to raise the cutter lever 44 to carry the cutting edge 45 thereof away from the surface 109 of the plate 54. As the disk 170 is fixedly secured to the wheel 152, it is constrained to 110 move in consonance with the latter and thus at each actuation of the clamp operating lever 125, the cutting lever 44 is likewise actuated. A ratchet disk 177 is fixedly secured upon the right-hand extremity of the shaft 117, as seen in Fig. 4, such disk being secured to the shaft as by means of a pin 178 passing through aligned openings in a hub 179 carried by the disk and a transverse opening in the shaft respectively. Mounted 115 to turn freely upon the hub 179 is a lever 180, such lever being retained upon the shaft by means of a plate 181 secured by a stud 182. A pawl 183 is pivotally secured at a point 184 to the lower portion of the lever 180, such 125 pawl having a tooth 185 adapted to engage ratchet teeth 186 upon the disk 177. At its opposite end the pawl has a spring 187 secured thereto, said spring having its opposite end secured to a lug 188 projecting from 130

the lever 180. A pin 189 also projects laterally from the lever 180 at a point below the axis of the pawl 183. As the ratchet disk 177 is fast to the shaft 117, it is evident that any turning of such disk will cause the shaft 117 with its pattern drum 116 to rotate. The peripheral surface of the pattern drum 116 is provided with a plurality of circumferentially spaced openings which may be internally screw threaded for the reception of pins or studs 190. While separate pins or studs such as 190 may be employed, it is also contemplated that elongated pattern indications such as 191 may be secured by means of screws or other devices engaging the openings in the peripheral surface of the pattern drum. The pins 190 or the elongated pattern cams 191 are so arranged as to engage the lugs 114 of the respective levers 110 above described, whereby, upon rotation of the drum, such levers will be actuated in accordance with the arrangement of the pattern studs or cams upon the drum.

In order to prevent overdriving of the drum 116 at the end of its movement, as well as to avoid accidental displacement or reverse rotation of the same, a pawl 192 is provided, such pawl having a locking tooth 193 for engagement with the ratchet teeth 186 and being pivoted upon a stud 194 engaging a boss 195 projecting from the bracket member 118. The locking pawl 192 is provided with a downwardly extending tail member 196 to which one end of a tension spring 197 is connected, the opposite end of this spring being secured to a pin 198 fixed in the supporting frame. The base member 6 of the supporting frame is provided with a series of parallel and substantially radial slots indicated at 199, 200, 201 respectively, see Fig. 3. Fitting within such slots are slide bars 202, 203, 204 respectively.

The slide member 202 is provided, adjacent its outer end, with an adjustable plate 205 secured thereto by means of screws 206, such plate being provided with elongated slots for the reception of such screws whereby the plate may be adjusted relative to the slide 202. The plate 205 has, at its outer extremity, an outstanding lug 207, said lug being provided with a downwardly extending notch or slot for the reception of the pin 189, above described. Upon the bar 202 is also secured an adjustable plate 208, such plate being connected thereto by screws 209. The plate 208 is provided with a laterally extending arm 210, which at its outer extremity, is arranged to lie behind a stud or pin 211 extending upwardly from the slide 203. A pivot stud 212 is secured in the base member 6, projecting upwardly therefrom, and upon said stud are pivotally mounted a pair of levers comprising the arms 213, 214 respectively. A stud 215 is secured in the outer end of the lever arm

213 and engages a laterally elongated slot in the inner end of the slide 202. A similar stud 216 projects downwardly from the end of the lever arm 214 and engages a transversely elongated slot in the inner end of the slide member 203. For permitting the free movement of the studs 215, 216 respectively, the flange member 7 of the base is provided with slots 217, 218. A plate 219 is fixed upon the upper surface of the arm 213 by means of screws 220. This plate 219 extends upwardly into a plane above that of the lever arm 213 where it is provided with a cam engaging element 221, the purpose of which will be described hereinafter. The lever comprising the arm 213 is extended to the opposite side of the pivot 212 to provide the cam engaging arm 222, while the lever comprising the arm 214 is also extended to the other side of the pivot 212 providing the cam engaging arm 223. As will be noted from inspection of Fig. 3, the arms 222 and 223 lie at different vertical levels.

In addition to the pin 211, the slide 203 is provided at its rear end with an adjustable plate 224 similar to plate 205 and having an upstanding lug 224^a, such lug being provided with a vertical slot for the reception of the pin 150 carried by the lever arm 138 as above described. The rear end of the slide 204 is also provided with an adjustable plate 225 having an upstanding lug 225^a provided with a vertical slot for the reception of a pin 161 carried by the lever arm 157. Fixed in the member 8 is a pivot stud 226 upon which is mounted a lever comprising the arm 227, such arm having depending from its extremity a stud 228 which engages an elongated slot in the forward end of the slide 204. This stud works in a slot 229 in the flange 8. The lever comprising the arm 227 extends to the opposite side of the pivot pin 226, providing the arm 230, from which depends the cam engaging stud 231. Secured to the upper surface of the lever arm 230 is a plate 232 which may be attached to such arm by means of a screw 233, the plate also having an opening for the reception of the pin 226. The plate 232 is bent upwardly as indicated at 234 and is provided with a portion 235 providing a cam engaging surface 236 which lies in a plane substantially above the plane of the lever arm 230.

For one of the clamping plates 5, by which the needles are secured in the needle cylinder, there is substituted a plate 5^a, such plate being provided with a pair of substantially parallel vertical slots 237, 238. These slots may be undercut or dove-tailed if desired, and within such slots are arranged the slide blocks 239, 240 respectively. Projecting outwardly from the outer surface of the plate 5^a is an ear 241, such ear being provided with a pair of spaced journal open-

ings corresponding to the two slots 237, 238 respectively. Shafts 242, 243 are arranged to turn in the respective journal openings, such shafts having circumferential grooves 5 with which engage the edges of a retaining plate 241^a secured to the ear 241 by means of a screw 241^b. Below the plate 241^a the shafts are of cylindrical form as indicated at 244, 245, being journaled at their lower 10 ends within brackets 246, 247 secured to the blocks 239, 240 respectively. The cylindrical portions 244, 245 of the shafts are provided with helical cam slots 248, 249 respectively, such cam slots being opposite the incline 15 as indicated in Fig. 15. Projecting outwardly from the bracket members 246, 247 are teated screws, such as 250, which engage the respective cam slots, the arrangement of parts being such that upon rotation 20 of the shafts 242, 243, in opposite directions, the screws 250 and therewith the blocks 239, 240 will simultaneously be raised or lowered. Secured to the upper ends of the shafts 242, 243 are spur gears 251, 252 25 respectively, such gears intermeshing for simultaneous operation. Fast to the shaft 242 is a lever member 254 and fast to the shaft 243 is a lever member 253, such lever members providing cam engaging elements 255, 256 respectively, at their outer extremities. A cam ledge 257 is secured by means 30 of screws 258 to the slides 239, 240, such slides thus serving to raise or lower the member 257 in accordance with the actuation of the levers 254, 253 respectively. This cam ledge 257 normally occupies the position indicated in Figs. 15 and 16, wherein it lies below the level of the cam engaging surfaces 221, 236 above described, and is 35 provided with peripheral cam surfaces 259, 259^a which, when properly positioned, serve to actuate the members comprising the cam elements 221 and 236 respectively. For operating the lever 253, a vertically movable 40 rod 260 is arranged for sliding movement in a vertical opening in a boss 261 projecting upwardly from the bed 1 of the machine. This rod 260 may be prevented from turning in the boss 261 by means of an outstanding pin 262 engaging a slot in the boss and is normally retained in depressed position by means of a coil spring 264 seated in an enlargement of the opening in said boss and which bears at its lower end upon 45 a transverse pin 260^a fixed in the member 260. The lower end of the rod 260 is provided with a cam surface 265 which may be engaged by cam lugs 266 carried by a master pattern chain 267, such chain passing over 50 a drum 268. The upper end of the pin 260 normally lies below the horizontal plane of the lever 254, but when lifted to the position indicated in dotted lines in Fig. 15, as by 55 the passage of the cam lug 266 beneath the same, such pin is engaged by the surface 255 of the lever 254 as such lever is carried around with the needle cylinder in its rotation. When the surface 255 strikes the relatively fixed pin 260, the lever 254 is rotated in a counter-clockwise direction as 60 viewed in Fig. 1, thus rotating the shaft 242 and through the gears 251, 252 rotating the shaft 243 in the opposite direction. Such movement of the respective shafts, with their helical cam slots, serves to elevate the cam 65 257 whereby to bring the surfaces 259, 259^a into a position such as to contact with the surfaces 221, 236 respectively as the needle cylinder continues to rotate. For restoring the cam 257 to its normal position, there is 70 provided a post or support 268 secured upon the bed of the machine by means of screws 269 or in other desired manner. This post extends upwardly to a point substantially 75 above the level of the cam lever 253 and is 80 provided with an overhanging portion 270 having a depending pin 271. This pin lies in the plane of the lever 253 and in a position to contact with the cam engaging surface 256 of the latter. Thus, as such surface is brought into contact with the stud 85 271, the lever 253 is caused to rotate in a counter-clockwise direction, thereby, through the gears 252, 251 and the helical cams, serving to restore the cam 257 to its normal depressed position. 90

Fixed to the needle cylinder is a cam 272, such cam providing a peripheral cam rise 273 followed by a second rise 274 and by a further rise 275, the cam then terminating in a radial drop 276. In a plane somewhat above the plane of the cam 272, there is provided a second cam 277, such cam having the peripheral rise 278 and the radial drop 279. A cam 280 is also fixed to the needle cylinder at a level somewhat above the cam 277, such cam having the cam rise 281 followed by a second rise 282 and terminating in the radial drop 283. 100

The operation of the mechanism above described is as follows, it being assumed that the yarn finger 32 is in operative position (Figs. 13 and 19), feeding the yarn to the stitch burr wheel and that the yarn fingers 33, 34 are in idle position. As indicated in Fig. 13, the yarn finger 32 is in a position to deliver its yarn Y at a point below the beards of the needles, such yarn extending to the left of the yarn changing apparatus toward the stitch burr wheel 19 which serves to place the yarn against the needle shanks and beneath the needle beards. As will be noted from inspection of Fig. 13, the yarn finger 32 is so positioned that the forward portion of the cam slot 40 engages the supporting pins 41, 42, the lug 114 of the actuating lever 110 resting against the peripheral surface of the pattern drum 116, the yarn finger having been brought to this position 115 by the action of spring 38 upon passage of 120

125

130

the pattern cam 191 from beneath the lug 115. At this time the yarn cutter 45 rests upon the surface 109 of the plate 54 as indicated in full lines in Fig. 14, the member 176 of the lever 52 lying in the space between adjacent cam teeth 172 of the wheel 170. The idle yarn guides 33, 34 are positioned as indicated in Fig. 19, having their ends resting against the ledge 103 of the plate 54 and having their yarns lying in contact with the upper surface of said plate. The idle yarn guide 34 lies between the flange 105 and a pin 284 upstanding from the plate 54, while the idle finger 33 lies between the latter pin and a second pin 285 also upstanding from said plate. A third pin 286 is spaced from the pin 285, and between the latter pins the yarn guide 32 extends when moved to idle position. In lieu of the pins 284, etc., thin plates might be employed, such plates extending between the idle yarn guides and forming partitions therebetween. With the parts as thus described, the ends of the idle yarns leading through the eyes of the yarn guides 33, 34 lie upon the upper surface of the plate 54 and beneath the spring clamp arms 60, 61 respectively, the extremities of such yarns extending laterally and beneath the foot member 108 and 30 to a position adjacent the cutter blade 45. If it is now desired that the yarns be changed, as for making a colored stripe in the fabric, a pattern lug 266 of the master pattern chain may be caused to lift the pin 260. As the needle cylinder rotates the lever 254, striking such pin is caused to swing in the manner above described, thereby lifting the member 257 with its cams 259, 259^a to its upper position. As the member 257 moves 40 past the surface 221 of the plate 219, the cam 259 strikes the surface 221 and the lever arm 213 is thereby caused to swing in a clockwise direction, thus pushing the slide member 202 outwardly. The outward movement of the slide member 202 serves to swing the lever 180, thereby causing the pawl 183 to engage a new tooth 186 of the ratchet disk 177. At the same time the arm 210 of the plate 208, by engagement with the pin 211 of slide 203, causes the latter to move outwardly, thereby swinging lever 138 and carrying pawl 145 into engagement with a new tooth 142 of the ratchet disk 141. During the latter part of such movement, the 50 arm 210 strikes the tail member 196 of the locking pawl 192, thereby raising the tooth 193 from the ratchet disk 177, whereby turning of the pattern drum shaft is freely permitted. As the member 257 continues to rotate, its cam 259^a strikes the surface 236 of the plate 232, thus swinging the lever arm 227 in a clockwise direction, thereby moving the slide 204 outwardly. The outward movement of the slide 204 serves to carry 60 the pawl 155 into engagement with a new tooth 154 of the ratchet disk 153. The function of the member 257 having now been completed, it may be restored to normal position by engagement with the stud 271, which stud may be located at any desired position upon the bed of the machine such that it will restore the levers 253, 254 to normal position before they reach the pin 260 again. As the needle cylinder rotates, the cam rise 273 of the fixed cam 272 first comes into engagement with the stud 231 of the lever arm 230, thereby positively swinging such arm in a counter-clockwise direction. As the other end of this arm is connected to the slide 204, the latter is moved inwardly and thereby, through the engagement of pawl 155, with the ratchet disk 154, the pattern wheel 152 is advanced one step. This movement of the pattern wheel 152, acting through the stud 135 and the clamp operating lever 125, serves to move the clamping slide 57 outwardly in its slot against the action of the spring 97, thereby withdrawing the clamp 61 laterally from above the idle yarns. At the same time the rotation of the cam disk 170 actuates the lever 52, whereby to raise the cutting lever 44 and to carry the cutting element 45 thereof away from the surface 109 of the plate 54. As the needle cylinder continues to rotate, the cam rise 281 of the fixed cam 280 comes into contact with the lever arm 222, rotating such arm in a counter-clockwise direction. Such movement of the lever arm 222 serves to move the slide 202 inwardly by the connection of the latter to the lever arm 213. This movement is permitted without affecting the position of the slide 203 by reason of the fact that the arm 210 of the slide 202 merely contacts with the pin 211 and has no positive connection therewith. The outward movement of the slide 202, through the lever arm 180 and the pawl 183, serves to impart a forward movement to the pattern drum 116. As the pattern drum is moved, the pins or cams thereon, in accordance with their predetermined arrangement, serve to swing the levers 110 and thereby to impart movement to the yarn guide fingers 32, 33, 34. If, for example, a pattern cam which has been holding the yarn guide 33 out of action, terminates during such forward movement of the drum, the lever 110 corresponding to such yarn guide 33 will be permitted to swing under the action of the corresponding spring 38 inwardly toward the pattern drum. As the yarn guide finger 33 moves outwardly under the action of its spring, the pins or rods 41, 42, which engage the outer portion of the cam 40 of the idle yarn guide, will cause such guide to move in such a manner as first to elevate its guide eye above the plate 54, then to carry such guide eye outwardly over the tops of the needles and then downwardly to a position 130

corresponding to the position indicated in full lines in Fig. 13. As the cam 280 continues to travel with the needle cylinder, the cam rise 282 is brought into engagement 5 with the lever arm 222, thus causing a further movement of the slide 202, thereby turning the pattern drum through a further arc of movement. Such movement may be sufficient to bring a pattern cam or 10 pin 191 into engagement with the lug 114 of the lever 110, thus swinging such lever in a clockwise direction as seen in Fig. 13, whereby moving the yarn guide 32 to idle position. As the yarn guide 32 moves inwardly toward 15 idle position, the formation of the cam slot 40 is such as to cause the yarn delivery eye first to rise substantially vertically to a plane above the tops of the needles and then to move inwardly over the needle tops and 20 then down into a position such as indicated in dotted lines in Fig. 13, where the now inactive yarn Y' (Fig. 22) is caused to lie over and slightly above the surface of the plate 54. As the idle yarn is drawn upwardly from the stitch wheel and inside the back line of the needles, it is caused to pass over the surface 109 of the plate 54 and beneath the cutting blade 45. The run of 25 yarn between the cutting blade and the guide eye lies against the vertical member 107 and substantially above the surface 300 of the foot member 108, being prevented from overthrow by the overhanging edge 107^a of the member 107; this run of yarn thus overlies 30 the active clamp member 60. As the needle cylinder continues to rotate, the cam rise 274 of the cam 272 causes a further rotation of the pattern wheel 152 and the pattern disk 170, thus allowing the stud 135 to drop off 35 the tooth of wheel 152 and thereby permitting the previously retracted clamp block 59 to return to clamping position. During such movement of the wheel 152, the member 176 of the cutter actuating lever rides on the flat 40 face 175 of the cam tooth with which it engages, thus retaining the cutter in elevated position. As the needle cylinder continues to rotate, the rise 275 of the cam 272 causes 45 a slight further rotation of the pattern wheel 152 and the disk 170, such movement having no effect on stud 135 but permitting member 176 to drop from the surface 175, thereby allowing the severing element 45 to drop upon surface 109 of blade 54. Such action 50 severs the now idle run Y' of yarn extending between the needles which have passed the stitch wheel and the yarn finger 32. During the movement of the clamp 55 block 59 inwardly along its guide groove, the lug 71 of the clamping arm travels up the inclined surface 85 of the corresponding cam block 83, thereby raising the end of the inactive clamp 61 to a point above the surface of the plate 54 and over all of the idle 60 yarns. The lug 71 then travels over the up- per horizontal surface of the cam block and then drops from the end of the latter, whereupon the spring 65 carries the clamp arm 61 down into contact with the plate 54, securely holding the idle run Y' as well as the other 70 idle runs of yarn thereagainst (Fig. 22). The stud 231 then runs off the end 276 of the cam 272, thus permitting the free actuation of the lever 230 in subsequent operations. The surface 222 also runs off the end of the cam 280 at substantially the same time whereby the lever 213 is free for further adjustment. Immediately thereafter, the fixed cam 277, having the cam rise 278, comes into contact with the surface 223 of the lever 75 comprising the arm 214. The slide 203 is thus moved inwardly thereby through the pawl 145 and the ratchet 142 actuating the pattern wheel 137. This wheel is moved through a sufficient distance by the cam rise 278 to carry one of the teeth 136 completely past the stud 134. This serves to swing the lever 124 about its pivot, whereby to carry its free extremity 130 outwardly, thereby moving the clamp block 56 outwardly in its 80 slot, see Fig. 7.

As the member 70 of the clamping finger 60 engages the cam surface 76 of the fixed block 72, the finger is raised slightly from the plate 54, thus preventing the clamping arm from dragging across the yarns thereon, it being understood that in the withdrawal of clamp block 59 to inactive position, a similar elevation of clamp finger 61 takes place. As the block continues to move outwardly the member 70 passes into contact with the inclined surface 84 of the block 82, thereby raising such block against the action of the spring 89 and permitting the member 70 to pass beneath the lower surface 86 of 90 said block and into a position such as indicated in dotted lines in Fig. 10. As the tooth 136 passes from beneath the stud 134, the spring 98 is permitted, through the lever 102, to move the block 56 inwardly, thus first raising the clamp lever by engagement of the member 70 with the surface 85 and then permitting such clamp lever to drop into contact with the inclined surface 76, thus permitting it gradually to engage the yarns without subjecting them to a blow such as might sever them. The movement of the clamp lever is thus such as to withdraw it from beneath the newly positioned idle run of yarn Y' and then to project such clamping member over such yarn as well as other idle yarns and thereafter to drop it upon the same (Figs. 23 and 24).

As the yarn guide 32 moves toward its active position, it will be observed that the end 125 of the yarn X extending from its guide eye is held securely beneath the active clamp member 60. As the yarn finger moves out and over the needle and then down into active position, such previously idle run of 130

yarn is caused to slice sharply down between two adjacent needles and as the yarn is caught between such needles, it is immediately drawn out from the newly positioned yarn 5 guide eye and carried into position for engagement by the stitch wheel (Fig. 21). By reason of the fact that the guide eye moves from within the needle circle and adjacent the yarn clamp to a position without the 10 needle circle, it is evident that the yarn must, of necessity, be placed under a certain amount of tension, and such tensioning of the yarn serves in a highly efficient manner to make certain its engagement by the blades 15 of the stitch wheel. It is also clear that by reason of the fact that the movement of the idle yarn guide from inactive to active position is occasioned by a cam fixed as respects the needle cylinder, the position of 20 entry of the yarn is accurately defined, this action being further assured by the moving of the previously inactive yarn guide across the needle circle in assuming active position. As the yarn guide assumes its active 25 position and its yarn commences to feed to the needles, the free end α' of such yarn which is held beneath the active clamp 60, is drawn out from beneath the same by pull of the needles (Fig. 22). As however, such 30 yarn is constrained to move outwardly around one of the posts 284, 285 or 286, it is prevented from contacting with the other idle yarns to a sufficient extent to drag the latter from beneath the clamp, while at the 35 same time during the movement of the yarn guide to idle position the posts 284, 285, etc., serve to localize the position of the idle run of yarn extending from the yarn guide eye in such a manner as to prevent the super- 40 position of such yarns beneath the clamping members such as might prevent the proper engagement of the latter with one or more of such yarns. It is evident that by arranging the pattern indications upon the 45 drum 116 in the desired manner, any proper succession of operation of the yarn guides 32, 33, 34 may be obtained, and by permitting the pattern pin 260 to remain in its upper position, a movement of the pattern 50 drum 116 may be caused to take place at each successive rotation of the needle cylinder. Thus the fabric may be provided with stripes of various colors and of one or more courses, such stripes being followed 55 by plain fabric for as great an extent as may be desired. It is thus possible by the use of a relatively small pattern drum 116 to provide colored stripes of complex pattern interposed between relatively wide sections of plain fabric, while at the same 60 time the overlap of the yarns at the changing point may be confined to relatively few needle wales and within sharply defined limits.

65 While but a single yarn changing device

has been indicated, it is contemplated that similar devices may be positioned at any desired interval about the circumference of the needle cylinder in which case the movable cam ledge 257 and the various fixed cams carried by the needle cylinder will serve to actuate the several changing devices in proper order. Thus in a machine using six feeds, a yarn changing device may be employed at each of such feeds with the 70 pattern indications so arranged as to change the yarns at each feed correspondingly, although it is obvious that if desired for any reason, the changing of the yarn at the different feeds could be made to take place in 75 80 different orders.

Having thus described the invention in a preferred embodiment of the same together with the mode of operation thereof, what I claim and desire to secure by Letters Patent 85 of the United States is:

1. A circular knitting machine comprising a row of relatively fixed needles, means for continuously moving said row of needles in a predetermined path while maintaining their tops in a predetermined plane, and a yarn guide movable from idle position at one side of the needle row and below the plane of the tops of the needles to a yarn feeding position upon the other side of the needle row and 90 also below said plane.

2. Yarn feeding mechanism, for use in a knitting machine having a row of needles, comprising a movable yarn presenting member provided with a guide element and means 100 for moving such guide element from a position at one side of the needle row and below the plane of the needle tops at yarn receiving position, to a similar point upon the opposite side of such needle row, and for causing such guide element in its movement to pass above 105 said plane.

3. A yarn feeding mechanism for knitting machines of that type employing a row of hooked needles, comprising a member having a guide eye normally positioned below the plane of the needle tops for presenting yarn to the needle hooks, and means operable successively for lifting said guide eye to a point 110 above the plane of the needle tops at yarn receiving position, for moving said eye transversely over the top of the needle row, and for depressing said guide eye to a position to 115 the rear of the needle row and below the tops of the needles.

4. A yarn feeding mechanism for circular knitting machines comprising a movable yarn finger having a yarn presenting element, and means for actuating said finger whereby to move said element through a path of substantially inverted U form extending from a point without the needle circle across the needle row to a point within the same.

5. In combination with a rotary needle cylinder having fixed needles therein, a yarn 130

- guide finger having a guide eye, and means for imparting bodily movement to such yarn finger whereby to move said guide eye from a feeding position outside the needle circle and below the plane of the tops of the needles. 6. In combination in a knitting machine having a series of relatively fixed needles, a yarn finger for presenting yarn to the needles, said finger having a guide eye and means for imparting bodily movement to said yarn finger whereby to carry said guide eye from a position at one side of and below the tops of the active series of needles, over said needles and to a position below the tops of and upon the other side of said needles. 7. In combination in a knitting machine, a needle cylinder having needles therein, an elongate radially disposed yarn finger having a yarn guiding element adjacent to its inner end movable from a position inside the needle row and below the level of the tops of the needles to a position outside thereof, means engageable with the yarn finger for moving it bodily in a longitudinal direction toward and from the needle cylinder, and cam means constraining said yarn finger to move bodily in a direction perpendicular to its first direction of movement. 8. A knitting machine comprising a series of needles, a bodily slideable yarn finger for presenting yarn thereto, said finger having a guide eye, a cam element carried by the said finger, said element comprising a plurality of distinct curved portions, spaced members engaging the curved portion of said cam element and collectively constituting the sole support for the finger, and means for imparting relative movement to said finger and said supporting members. 9. A knitting machine comprising a circular series of needles, a yarn guide finger movable in a plane radial of said needle circle, said yarn finger having a cam slot of substantially W shape and a pair of fixed and spaced pins engaging said cam slot. 10. In a knitting machine, in combination a series of needles, a bodily movable yarn finger having a guide eye, and cam and spring means alternately operative respectively for imparting movement to said finger whereby to carry said guide eye from a position behind the needles and below the tops thereof, upwardly over the tops of said needles and to a position upon the other side thereof and in a plane below their tops. 11. In a knitting machine, in combination a rotary needle cylinder supporting a series of relatively fixed needles, and means for feeding yarns to the needles, said means comprising a bodily movable yarn finger, pattern means for moving said finger to an inoperative position wherein its delivery end lies behind the tops of the needles, and spring means for restoring such finger to normal feeding position, with its delivery point on the other side of the needles. 12. In combination with a circular rotat- ing cylinder knitting machine having fixed needles, a movable yarn finger having a yarn guide eye, said guide eye when inoperative occupying a position within the needle circle and below the plane of the needle tops at the yarn feeding point, and means rotating with the needle cylinder for determining movement of said guide eye to an operative position outside the needle circle whereby to introduce its yarn at a certain and predeter- 70 75 80 85 90 95 100 105 110 115 120 125 130
 hind and below the tops of the needles, and spring means for restoring such finger to normal feeding position, with its delivery point on the other side of the needles. 13. A fixed needle, rotary cylinder knitting machine having a rotatable stitch burr arranged outside the needle circle, a movable yarn presenting finger having a guide eye which in inoperative position lies within the needle circle and below the plane of the tops of the needles, and clamping means arranged closely adjacent such eye when in inoperative position for holding the end of the idle yarn, whereby upon movement of such guide eye to operative position outside the needle circle the yarn is presented to said burr under substantial tension. 14. A feed mechanism for circular knitting machines having a yarn clamp comprising a yarn engaging element, a plurality of movable yarn carriers for placing yarns in engagement with said element, and a plurality of members outstanding from said element and constituting separators for said carriers and their respective yarns. 15. A feed mechanism for knitting machines comprising a yarn clamping device having a yarn supporting table, a movable yarn carrier for laying a yarn across said table, and a pair of spaced and substantially parallel members upstanding from the surface of said plate and providing between them a channel for the reception of said carrier. 16. A feed mechanism of the class described comprising a yarn clamping device having a yarn supporting surface, a plurality of movable yarn fingers, means for moving said yarn fingers whereby to lay yarns across said surface and a plurality of partition members associated with said surface and defining independent compartments for the reception of the respective fingers. 17. A feeding mechanism for circular knitting machines comprising a support within the needle circle, a yarn severing device mounted upon said support immediately behind the needles, a radially movable yarn feeding element, a clamping finger cooperat- ing with said support, said finger being disposed inward of said severing device and normally intersecting the radial plane of

movement of the feeding element, and yarn separating elements upstanding from said support and terminating closely adjacent to said finger.

- 5 18. A feed mechanism for circular knitting machines comprising a support within the needle circle and immediately behind the needles, a yarn severing device mounted upon said support, a plurality of yarn feeding elements movable into cooperative relationship to said support whereby to lay yarns radially thereacross, an elongate movable clamping element normally extending across the radial planes of movement of the 10 15 several feeding elements for simultaneously engaging yarns resting on said support, and means for limiting movement of yarns in a direction longitudinal of said clamping element.
18. A feed mechanism for knitting machines comprising a clamp for idle yarns having a yarn engaging surface, a plurality of substantially parallel pins upstanding from said surface, and a plurality of yarn 20 25 manipulating devices receivable within the spaces between adjacent pins and operative to place yarns into engagement with said surface.
20. A feed mechanism for a circular knitting machine having a feed point external to the needle circle, comprising a support within the needle circle substantially radially inward of the feed point, a yarn severing device immediately within the needle circle 30 35 carried by said support, said severing device being beyond said feed point in the direction of knitting, a yarn clamping jaw carried by said support substantially opposite the feed point, a plurality of yarn feed 40 45 fingers movable radially from without the needle circle across the latter to carry their respective yarns radially across the clamping jaw, and means carried by said support to prevent the improper withdrawal of yarn from engagement with said clamping jaw.
21. A knitting machine having yarn clamping means comprising a clamping lever pivoted adjacent one of its ends and a bow spring having one extremity engaging said lever at a point removed from its pivot, said bow spring extending over said pivot and having its opposite extremity fixedly secured as respects said pivot, and a movable feeding finger for introducing an idle run of yarn into the clamping means.
22. Yarn clamping mechanism for a knitting machine comprising a slidable block, a yarn clamping lever pivotally secured to said block and a spring for actuating said lever, said spring having one extremity secured to said block and extending transversely across the pivot of the lever, and having its free extremity engaging the clamping lever at a point between its pivot 50 55 60 65 and the end of said lever.

23. A yarn clamping device for knitting machines comprising a pivoted clamping lever and a spring for actuating the same, said spring being of elongated form and supported at one extremity, the opposite end of said spring being provided with spaced ears lying upon opposite sides of said clamping lever.

24. A circular knitting machine having a rotating needle cylinder, yarn manipulating instrumentalities comprising a pawl and ratchet mechanism, a pattern controlled cam mounted upon said needle cylinder and optionally movable into position to advance the pawl into engagement with a new tooth of its ratchet, and a fixed cam rotatable with the needle cylinder for moving the pawl to impart movement to the ratchet.

25. A circular knitting machine having a rotatable needle cylinder, yarn manipulating instrumentalities including a pattern drum, means including a pawl and ratchet for intermittently rotating said drum, reciprocable means connected to the pawl, a cam mounted upon the needle cylinder and optionally movable into a position for moving said reciprocable means in one direction, and a fixed cam upon said cylinder for moving said reciprocable means in the opposite direction.

26. A circular knitting machine having a rotatable needle cylinder, a cam mounted upon said cylinder and adjustable thereon in an axial direction, a second cam fixed upon said cylinder, yarn manipulating instrumentalities including a reciprocable slide, and means whereby said slide may be moved in one direction by said first cam and in the opposite direction by said second cam.

27. A circular knitting machine having a rotatable needle cylinder, yarn manipulating instrumentalities carried by a fixed support arranged outside the needle circle, and actuating mechanism for said instrumentalities including a cam carried by said cylinder and movable from operative to inoperative position and vice versa, a movable pattern controlled element for moving said cam to operative position, and a fixed element for restoring said cam to normally inoperative position after each actuation thereof by said pattern controlled element.

28. A circular knitting machine having a rotatable cylinder and fixed needles therein, yarn manipulating instrumentalities including yarn presenting, yarn clamping and yarn severing means, and mechanism for actuating said instrumentalities in properly timed relation, comprising a plurality of cams fixedly secured to the rotating cylinder, said cams being normally inoperative to effect movement of the respective instrumentalities, and means including a cam movably mounted upon the cylinder for rendering

said fixed cams operative at seasonable times.

29. A circular knitting machine having a rotatable needle cylinder, a plurality of movable yarn presenting members, yarn clamping means including independently movable members, a yarn severing member, pattern drums for controlling the several members, brake means for certain of said drums, pawl 10 and ratchet drive means for said drums, detent means for positively preventing overthrow of one of said drums, and cam means rotating with the needle cylinder for releasing said detent, and for actuating said pawl 15 and ratchet means in timed relation to the rotation of the needle cylinder.

30. In combination with a rotating cylinder knitting machine, yarn manipulating instrumentalities, and mechanism for actuating said instrumentalities, said mechanism comprising a plurality of pattern drums, means including pawls and ratchets for driving the several drums, a pattern controlled cam carried by the needle cylinder 25 and optionally movable into position whereby to cause engagement of the several pawls with advanced teeth of their respective ratchets, and a plurality of fixed cams mounted upon the cylinder and operative to 30 actuate the respective pawls to rotate the corresponding drums.

31. A knitting machine comprising a rotating needle cylinder, yarn changing means fixedly positioned outside said cylinder, said 35 means comprising a pawl actuated pattern shaft, a pawl carrier oscillatable about the axis of said shaft, a pawl carried thereby, a rectilinearly movable slide engaging said pawl carrier, a lever having connection with 40 said slide, said lever comprising a pair of oppositely directed arms, a pattern controlled cam carried by said needle cylinder for actuating one of said arms, and a fixed cam carried by said cylinder for actuating 45 the other of said arms.

32. A knitting machine comprising in combination a rotating needle cylinder, a fixed support arranged adjacent said cylinder, rotatable pattern means carried by said 50 support, an oscillatory element for actuating said pattern means, a slide bar arranged within said support and having one extrem-

ity engaging said element, a two armed lever pivoted upon said support to turn about a vertical axis, said lever having connection 55 with the other end of said bar, and cam means carried by said cylinder for engaging the respective arms of said lever, whereby successively to move said slide bar in opposite directions.

33. A knitting machine comprising in combination a rotating needle cylinder, a yarn changing mechanism comprising relatively movable parts, and means carried by said cylinder for imparting movement to 65 certain of said parts, said means comprising a cam ledge movable vertically of the needle cylinder, a shaft journalled upon said cylinder and movable therewith, a helical cam groove on said shaft, means carried by said cam ledge for engaging said groove, and means whereby said shaft may be turned during the rotation of the needle cylinder.

34. In combination of a knitting machine having a rotatable needle cylinder and yarn feeding mechanism, a cam carried by said needle cylinder and movable vertically as respects the same, said cam having studs projecting therefrom and a pair of parallel shafts having oppositely inclined cam 80 grooves therein, said grooves respectively engaging the studs projecting from said movable cam, and means for turning said shafts in opposite directions whereby to move said cam vertically.

35. A knitting machine having in combination yarn changing mechanism and a rotatable needle cylinder, means for imparting movement to said yarn changing mechanism comprising an adjustable cam ledge carried 90 by the needle cylinder and means for adjusting said cam ledge, such means comprising a pair of substantially parallel shafts, means connecting said shafts for simultaneous rotation in opposite directions, oppositely inclined cam elements carried by said shafts, said elements being constructed and arranged to impart movement to said cam ledge and means whereby one of said shafts may be caused to rotate alternately in opposite directions.

Signed by me at Pawtucket, Rhode Island, this 22nd day of July, 1921.
MAX C. MILLER.
